UNITED STATES PATENT OFFICE.

JULIUS A. HORVITZ, OF NEW BEDFORD, MASSACHUSETTS, ASSIGNOR TO CROWN AUTOMOTIVE CO., INC., OF NEW BEDFORD, MASSACHUSETTS, A CORPORATION OF MASSACHUSETTS.

DESIGN FOR A RADIATOR CAP.

Application filed December 31, 1923. Serial No. 8,198. Term of patent 7 years.

To all whom it may concern:

Be it known that I, JULIUS A. HORVITZ, a citizen of the United States, residing at New Bedford, in the county of Bristol and State of Massachusetts, have invented a new, original, and ornamental Design for a Radiator Cap, of which the following is a specification, reference being had to the accompanying drawing.

The figure is a perspective view of a radiator cap embodying my new design.

I claim:

The ornamental design for a radiator cap as shown.

JULIUS A. HORVITZ.
